UNITED STATES PATENT OFFICE.

IRVING J. FOLTZ, DECEASED, LATE OF SEATTLE, WASHINGTON, BY FLORENCE O. FOLTZ, EXECUTRIX, OF SEATTLE, WASHINGTON.

OIL BURNER.

Application filed December 13, 1923. Serial No. 680,316.

To all whom it may concern:

Be it known that IRVING J. FOLTZ, deceased, late a citizen of the United States, and resident of the city of Seattle, in the 5 county of King and State of Washington, did invent certain new and useful Improvements in Oil Burners, of which the following is a specification.

My invention relates to burners of the 10 type which are intended for burning oil, and particularly a medium or heavy grade of oil, and for such purposes as heating of furnaces, and such other purposes where the capacity for making of a flame of considerable 15 size and heating possibilities is desirable.

The object of my invention is to make a burner which will efficiently handle such oil for the purposes mentioned, and further, 20 specifically to make such a burner having the capacity for being regulated so as to burn a very small amount of oil with a consequent reduction in the heating capacity.

The novel features of my invention will 25 be hereinafter specifically pointed out in the claims.

The accompanying drawings show my invention in the form of construction which I now prefer to use.

30 Figure 1 is a longitudinal section through the burner upon a central vertical plane, and Figure 2 is a corresponding section on the horizontal plane.

The main body of this burner consists of 35 a tubular body 1, having mounted within and concentric therewith a central pipe or tubular body 3. These may be separate members or may be connected integrally as by two or more plugs or webs 30. An air 40 delivery pipe as 8 is connected to the outer end of the larger tubular member 1. This pipe 8 is supposed to be supplied with air under pressure. This pressure need not be very great, but should be sufficient to produce a draft through the burner of sufficient strength to somewhat atomize the oil fed thereto even when the burner is turned down low.

In the construction illustrated in the 50 drawings, the two concentric tubular members 1 and 3 are supposed to be different parts of the same casting. The inner tube 3, which is the oil atomizing tube, preferably has its inner or discharge end 31 interiorly 55 shaped as an expanding cone, that is a cone

with the large end towards the flame. The outer member 1 is preferably also somewhat contracted around the discharge end of the inner tube 3. This may be effectively and conveniently done by providing the inner or discharge end thereof with a detachable ring 4 having a flange 40 which extends towards the center so as to provide a relatively reduced annular discharge opening between the same and the tube 3. Preferably the 60 flange 40 which determines the outer diameter of the supplemental air discharge orifice, is located slightly backward or towards the outside from the extreme inner end of the atomizing tube 3. The ring 4 is shown as 65 secured in place upon the outer tube 1 by a set screw as 42. It is also provided with a ledge 41 extending horizontally from its lower side, to which is connected a plate 50, which is cupped enough to retain in its upper 70 surface a plate 5 of some refractory material, preferably a material made from some clay product.

This plate 5 will become highly heated by the flame issuing from the burner nozzle. 80 When so highly heated it is possible to reduce the supply of oil to a very low amount, thus producing only a very small flame. This possibility arises from the fact that the highly heated body 5 will function substantially 85 the same as a pilot flame, so as to maintain the heating flame ignited even when it is turned down to a minimum.

One of the webs 30 by which the atomizing tube 3 is held in position is provided 90 with a bore 61 leading to the outside of the tube 1. A lug provided on the outside of this tube is also provided with a bore 60 intersecting the bore 61 with which is connected the oil supply pipe 6.

The burner as a whole, consisting of the inner and outer tubes 1 and 3 and the ports carried thereby, is mounted upon a plate 10 to which it may be detachably secured by means of side lugs 11 and bolts passing 95 therethrough. The outer end of the tube 1 may be provided with an enlarged flange or cup-shaped member 2 to which the air supply pipe 8 is connected. A metal casing 7 is preferably mounted upon the outer 100 periphery of the plate 10 and of such a length as to correspond with the wall in which the burner is mounted. This forms a convenient way of mounting the burner and of providing a suitable chamber, which is 105 110

connected with, but not a part of the furnace chamber. The burner is thus assembled as a unit and may be mounted in the wall by any ordinary workman.

- 5 I have found that the above burner, while being effective in producing large quantities of heat when supplied with a quantity of oil, is also capable of being regulated down to a very small flame without danger of 10 the flame being extinguished. The oil which is supplied through the pipe 6 drips into the atomizing tube 3. The current of air passing therethrough atomizes or sprays it sufficiently to produce effective combustion. 15 The supplemental air passing through the annular space between the outer and inner tubes 1 and 3, acting upon the spray as discharged from the inner tube, further contributes towards perfect combustion. 20 One advantage of making the flange 40 as part of the ring 4, which is separate from the tubular members 1 and 3, is that it may be adjusted axially relative to the latter. By moving the flange 40 outwardly 25 of the discharge end 31 of the tube 3, the air currents issuing from the end 31 and flange 40 will be affected in such manner as to cause spreading of the oil spray, and thus to spread the flame. Movement of the 30 flange 40 in the opposite direction will act

in the reverse manner to decrease the spread of the flame.

What I claim as my invention is:

1. An oil burner having an inner tube and means for discharging oil thereinto from one side, a concentric surrounding tube spaced therefrom to form an annular passage, the outer wall of said annular passage being at its outer end reduced in diameter and terminating just back of the outer discharge end of the inner tube, and a common air supply connection for both said tubes. 35

2. In an oil burner, an inner and an outer tube integrally secured to form an annular passage between them, an oil supply pipe discharging at the top side of the inner tube, the bore of the discharge end of the inner tube being enlarged to reduce the walls thereof to a thin edge at its end, and 40 a cap fitting the discharge end of the outer tube and restricting the annular passage adjacent to the discharge end of the inner tube, and a common air supply connection to both tubes. 45

Signed at Seattle, King County, Washington this 2nd day of November, 1923.

FLORENCE O. FOLTZ,
Executrix of Irving J. Foltz, deceased.
